UNITED STATES PATENT OFFICE.

FREDERICK W. LETSCH, OF BALTIMORE, MARYLAND.

MULTIPLE MAGAZINE FOR TYPOGRAPHIC MACHINES.

1,410,331.

Specification of Letters Patent. Patented Mar. 21, 1922.

Original application filed March 15, 1918, Serial No. 222,760. Divided and this application filed July 21, 1920. Serial No. 397,883.

To all whom it may concern:

Be it known that I, FREDERICK W. LETSCH, a citizen of the United States, and residing at Baltimore city, Maryland, have invented 5 certain new and useful Improvements in Multiple Magazines for Typographic Machines, of which the following is a specification.

This invention relates to a multiple magazine for typographic machines and particularly machines of the kind described in my copending application, Serial No. 222,760, filed March 15, 1918, of which the present application is a division.

15 It is the object of the invention to provide a multiple magazine which can be employed with a typographic machine having a single distributor and a single assembling mechanism, and which can be easily and 20 quickly adjusted so as to bring any desired section of the magazine into cooperative relation with the distributor and assembling mechanism. A further object of the invention is to provide a construction which can 25 be so positioned that the various sections of the magazine can be easily withdrawn therefrom and other sections substituted. A still further object is to provide a mechanism of the kind referred to which is simple 30 in construction and operation and which can be easily manipulated to place the same in any desired position.

The invention is set forth in the following specification and illustrated in the accompanying drawings in which:

Figure 1 is a front view of the upper portion of a typographic machine showing the invention applied thereto;

Figure 2 is a side elevation of the construction appearing in Figure 1;

Figure 3 is a side elevation of the multiple magazine involving the present invention showing certain details of construction and also the relation of the magazine to other 45 parts of the machine;

Figure 4 is a detailed view illustrating the matrix escape pawls used in each section of the multiple magazine.

Referring to the drawings in detail, 10 50 represents the framework of a typographic machine to which the multiple magazine of the present invention is applied.

The distributing mechanism of the machine is generally designated by the numeral 55 11 from which the matrices are dropped into

the chutes 12 which serve to conduct them into the magazine. Other chutes 13 are provided for conducting the matrices from the magazine to the assembling mechanism. It will be understood that when any particular section of the multiple magazine has its lower end adjusted to register with the assembler chutes 13, its upper end will register with the chutes 12 of the distributing mechanism.

60 The multiple magazine of the present invention comprises a frame which consists of three parts 14, 15 and 16, suitably secured together in offset or stepped relation and in which three magazine sections 17, 18 and 19 are removably mounted. Each of the magazine sections is supported at its front and rear ends and the rear end of each magazine has connected with it a transverse bar B which is adapted to engage between 65 suitable bars B' secured to the various parts of the frame. The magazine frame is provided with trunnions 20 which are rigidly secured to one of the parts thereof, these trunnions being arranged near the center 70 of gravity of the frame. These trunnions carry rollers 21 which are adapted to run on tracks 22 secured to the framework of the machine. The lower section 14 of the magazine frame carries at the rear a bracket 75 23 in which a wheel 24 is rotatably mounted, this wheel being adapted to enter a recess or socket 25 in a bracket 26 secured to the frame of the machine. The upper section of the frame near its front end is 80 provided with a handle 27 by which the magazine frame may be moved to various positions. Each part of the magazine frame is provided on each side with pins 28 which are adapted to engage with suitable notches 85 provided in brackets 29 secured to the framework of the machine, this arrangement constituting means for holding the magazine frame in various positions. Means are also provided for locking the 90 magazine frame in different positions, such means comprising a spring bolt 30 mounted in the framework of the machine and positioned to engage holes 31 in the various parts of the magazine frame.

105 Each of the magazine sections is provided at its lower portion with suitable matrix release pawls 32 which are operated by push rods 33 connected to the keys (not shown) constituting the keyboard of the 110

machine, it being understood that these parts are the same or analogous to those generally employed in machines of this character.

5 Briefly referring to the operation of the mechanism it will be understood that the parts are so proportioned that the magazine sections and the parts of the frame are slightly heavier in the rear of the trunnions 20 than in front so that the frame when not locked in operative position has a tendency to rotate upon said trunnions until the wheel 24 rests in the socket 25 of the bracket 26. When it is desired to 10 change the position of the magazine so that a different section may be brought into register with the distributor and assembler chutes the bolt 30 is withdrawn and by means of the handle 27 the entire 15 magazine may be rotated about the trunnions 20 and can be moved along the track-way 22 of the rollers 21. Any section of the magazine can thus be brought into register with the distributing and assembling 20 mechanism. And when the magazine is thus unlocked it may be rotated about the trunnions 20 into a horizontal position with the wheel 24 resting in the socket 25 so that sections of the magazine may be 25 removed from the frame by disengaging the bars of the magazine sections from the bars B' secured to the various parts of the frame. The construction as a whole therefore can 30 be easily manipulated to place different sections of the magazine in register with the other mechanism of the machine and also positioned so that removal and replacement of the magazine sections can be easily accomplished. 35

40 It is apparent that various modifications and details of construction may be employed within the scope of the invention and without departing from the spirit thereof as embodied in the appended claims.

45 Having thus described the invention what I claim as new and desire to secure by Letters Patent is:

1. In a typographic machine in combination, a plurality of magazines for receiving and holding matrices, an inlet chute and an outlet chute for directing matrices into and from the magazines, a frame upon which said magazines are removably supported, said frame including a plurality of sections 50 arranged in stepped relation, one section for each of said magazines, a trunnion on each side of said frame, a wheel on each of said trunnions, a horizontal track on each side of said frame, said frame being tiltable upon 55 said trunnions and movable bodily along said tracks, whereby different magazine sections are brought into register with said chutes, a pin on each of said frame sections 60 near the front end thereof, a fixed member having a notch adapted to receive one of 65

said pins to position and hold the frame as different magazines are presented to the chutes, and cooperating means on each of said sections and the machine frame for locking the magazine frame in different positions. 70

2. In a typographic machine in combination, a plurality of magazines for receiving and holding matrices, an inlet chute and an outlet chute for directing matrices into and from the magazines, a frame upon which said magazines are removably mounted, said frame including a plurality of sections arranged in stepped relation, one section for each of said magazines, a trunnion on each side of said frame, the portion of the frame in the rear of the trunnion being slightly heavier than the portion in front of the same, a wheel on each of said trunnions, a horizontal track on each side of said frame, said frame being tiltable upon said trunnions and movable bodily along said track to bring different magazine sections in register with said chutes, a pin on each of said frame sections near the front end thereof, a fixed bracket having a notch adapted to receive one of said pins to position and hold the frame as different magazines are presented to the chutes, a roller mounted beneath the rear of said frame and a stationary bracket having a depression adapted to receive said roller when said frame is arranged in a horizontal position. 75 80 85 90 95

3. In a typographic machine in combination, a plurality of magazines for receiving and holding matrices, an inlet chute and an outlet chute for directing matrices into and from the magazines, a frame upon which said magazines are removably supported, said frame including a plurality of sections arranged in stepped relation, one section for each of said magazines, a trunnion on each side of said frame, a wheel on each of said trunnions, a horizontal track in each side of said frame, said frame being tilttable upon said trunnions and movable bodily along said tracks whereby different magazine sections are brought into register with said chutes, a pin on each of said frame sections near the front end thereof, a fixed member having a notch adapted to receive one of said pins to position and hold the frame as different magazines are presented to the chutes, each of said sections also having adjacent its front end a hole, and a spring bolt on the machine frame adapted to enter one of said holes and lock the magazine frame in position as different magazines are presented to the chutes. 100 105 110 115 120

4. In a typographic machine in combination, a multiple magazine comprising a magazine frame formed of a plurality of sections arranged in stepped relation and a magazine removably supported on each of said sections, said frame having a trunnion 130

at each side and so arranged that the portion of said frame in the rear of the trunnions including the magazines, is heavier than the portion in front of the same, a wheel on each of said trunnions, a horizontal track for each of said wheels, said frame being tiltable upon said trunnions and movable along said track to move the magazines into different positions, means adjacent the front

end of said frame for positioning and locking the frame with the magazines in inclined position, and means for supporting the rear end of said frame when the same is arranged in a substantially horizontal position.

15

In testimony whereof I affix my signature.

FREDERICK W. LETSCH.
